LAMP SHADE

Evelyn T. Whitmer, Phoenix, Ariz.

Application April 15, 1949, Serial No. 2,034

Term of patent 14 years

(Cl. D48—16)

To all whom it may concern:

Be it known that I, Evelyn T. Whitmer, a citizen of the United States, residing at 3211 West Van Buren, Phoenix, in the county of Maricopa and State of Arizona, have invented a new, original, and ornamental Design for Lamp Shades, of which the following is a specification, reference being had to the accompanying drawings, forming part thereof.

Figure 1 is a perspective view of a lamp shade, showing my new design.

Figure 2 is a side elevation showing the side opposite to Figure 1.

Figure 3 is an elevational end view of the lamp shade.

I claim:

The ornamental design for a lamp shade, as shown.

EVELYN T. WHITMER.
